UNITED STATES PATENT OFFICE.

GEORGE GLEASON, OF AUBURN, NEW YORK.

CATTLE-STANCHION.

1,086,157.

Specification of Letters Patent.

Patented Feb. 3, 1914.

Application filed September 10, 1912. Serial No. 719,676.

To all whom it may concern:

Be it known that I, GEORGE GLEASON, a citizen of the United States, residing at Auburn, in the county of Cayuga and State of New York, have invented certain new and useful Improvements in Cattle-Stanchions; and I do hereby declare the following to be a full, clear, and exact description of the invention, such as will enable others skilled 10 in the art to which it appertains to make and use the same.

The present invention relates to cattle stanchions, and consists in the combinations and arrangement of parts disclosed in the 15 following specification and particularly set forth in the claim.

The invention has for its purpose to improve over the cattle stanchion disclosed in my U. S. Patent #1,030,724, dated June 25, 20 1912, to the end of providing a construction wherein the hinged section for opening the yoke to apply same on the neck of the animal is provided with means for reinforcing the pivotal connection between the rigid 25 part and opening section, and for limiting the extent of opening of the pivoted section, thus making the yoke more convenient for handling and ready in its application.

With these and other objects in view the 30 invention consists in the novel details of construction and combinations of parts more fully hereinafter disclosed and particularly pointed out in the claim.

Referring to the accompanying drawings 35 forming a part of this specification in which like numerals designate like parts in all the views:—Figure 1 is a front elevational view of the improved construction of the Y-piece, and showing its manner of application to 40 the yoke side members; Fig. 2 is a side elevational view thereof; Fig. 3 is a top plan view of the same; Fig. 4 is a side elevational view showing the hinged mount of the swinging section, and the device which 45 limits its extent of opening; and Fig. 5 is a top plan view of Fig. 4.

Referring to the construction in detail, the device consists of a pair of tubular bars 1 and 2, one of the bars thereof having its end 50 portions 3 and 4 fitting within the legs 5 and 6 of the Y-pieces, as clearly shown in Fig. 1. A pair of rivets 7 secure the ends of the bar 1 within sockets provided by the Y-pieces 5 and 6, and said rivets pass through 55 said Y-members and the yoke bar 1, and are

upset on the outer sides of said Y-members, as clearly shown in Figs. 1 and 3.

Each Y-member consists of two cast sections 8 and 9 of similar design, and which are secured together through the medium of rivets 10 which pass through lugs 11 formed integral with said sections. A head 12 provides the swivel supports for the Y-members, and is adapted to fit within a suitable recess formed in one of the stall heads; and a bead 13 formed on said head adjacent the lugs 11 is adapted to bear against the surface of the stall head around said opening. A suitable locking pin 23 is slidable within the head 12 of the lower Y-member and is operable, by means of a ring 24 held in a link 25 passing through an eye 26 in the pin, to engage and disengage a corresponding recess formed in the stanchion support, thereby securing the same in place to revolve 75 horizontally.

The respective side edges of the sections forming the head 12 are provided with a groove 14 and a projecting edge 15, which are complementary to each other and interengage, and by reason of which relative lateral slipping of the Y-sections is prevented.

The swinging bar 2, by which the yoke is opened for attachment to the animal's neck, is pivotally mounted between a pair of lugs 17 formed on an enlargement 18 at the end of the lower Y-piece, and a pin or bolt 19 passes through said lugs and said swinging bar and provides the pivotal bearing. To 85 limit the extent of opening of the swinging bar 2, the same has secured thereto at its lower end a finger 20, said securing means consisting of a screw 21 and a nut 22 which clamp said finger against the inner wall of the tube, as shown in Figs. 4 and 5. The finger projects within the tube of the rigid side section 2, and is adapted to engage with the inner side wall thereof when said swinging section is opened in that manner indicated by broken lines in Fig. 4. And when in closed position the finger lies against the opposite inner side of the rigid section 2, and acts in the capacity of a brace for making a rigid pivotal connection between the 95 hinged parts.

The upper Y-piece is provided with a collar 27 formed with a depending semi-circular flange 28 adapted to receive thereinto and limit the movement of the upper end of 110

the swinging bar 2, as shown in Figs. 1 and 2.

A gravity-operated latch 29 may be placed within the leg of the Y-piece, adapted to 5 slide down within the upper end of the hollow bar 2 for securing the same in closed position. A finger piece 30 for operating the latch 29 to release the bar 2, projects through a slot 31 in the Y-piece, said finger 10 piece also serving the purpose of limiting the downward movement of said latch.

It is obvious that those skilled in the art may vary the details of construction and arrangement of parts without departing from 15 the spirit of my invention, and therefore I do not wish to be limited to such features, except as may be required by the claim.

What I claim is:—

A cattle stanchion comprising a pair of 20 tubular Y-members provided with swivel supports; the two legs of one of said Y-members provided respectively with a socket, and a pair of lugs; the two legs of the other of said Y-members provided respectively with a socket 25 and a projecting flange forming a stop member; a tubular bar fitting within the sockets of

said Y-members and rigidly connecting said members together; a tubular bar pivotally mounted between said lugs and adapted to engage with said stop member and form a closed yoke; a gravity operated bolt slidably mounted within the yoke leg adjacent the free end of the pivoted bar and adapted to engage with and lock said bar in closed position; and a rigid member detachably secured within said pivoted bar and projecting within the leg of the adjacent Y-member, said rigid member adapted to engage with said leg of the Y-member and form a brace for the yoke when the pivoted bar is in closed position, and to engage with the opposite face of said Y-member and provide a stop for limiting the opening movement of said pivoted bar when the yoke is opened, substantially as described.

In testimony whereof, I affix my signature, in presence of two witnesses.

GEORGE GLEASON.
